UNITED STATES PATENT OFFICE.

JAMES A. KINNEY, OF LEBANON, PENNSYLVANIA, ASSIGNOR TO BETHLEHEM STEEL COMPANY, OF BETHLEHEM, PENNSYLVANIA, A CORPORATION OF PENNSYLVANIA.

BOLT-HEAD TRIMMER.

Application filed December 12, 1921. Serial No. 521,815.

The present invention relates to machines for trimming bolt heads or similar articles, and has for its object the provision of a machine of this character having novel means incorporated therewith for promptly ejecting the bolts or other work at the completion of the trimming operation.

One form of the invention, which may have various embodiments, is illustrated in the accompanying drawings in which:

Fig. 1 is a section through a portion of a bolt head trimming machine having the invention incorporated therewith;

Fig. 2 is a section on line 2—2 of Figure 1;

Fig. 3 is an end elevation of the machine as seen from the left, Figure 1; and

Fig. 4 is an enlarged sectional view through a portion of the trimming mechanism.

The table 10 is supported on legs 11 and this table slidably supports in its recessed upper surface a frame 12 which carries a plunger 13. This plunger comprises a substantially cylindrical member the forward portion of which has threaded relation with the frame 12 so as to be adjustable relatively thereto. The extreme forward end 13' of the plunger, which lies in front of frame 12, is reduced in section, having a vertical bearing face of slightly less diameter than that of the bolt heads to be trimmed. This portion 13' has a central cylindrical aperture to alternately receive the shank of a bolt and the spindle 15' which projects forwardly from a piston 15 slidably contained in the hollow interior of the plunger. Piston 15 is normally pressed toward the forward end of the plunger, as shown in Figure 1, by the coiled spring 16. The rear end of the plunger 13 is provided with a plug 17 which serves as an abutment for the rear end of the spring and this plug has an aperture 17' for the free passage of air into and out of the interior of the plunger.

A die plate is indicated at 18, this plate being secured to the end of the table 10 in a vertical position and having an opening 18' therein which corresponds to the desired outline of the finished bolt heads. The opening 18' of the die is in register with the flaring opening 10' in the table and bolts which are driven through the die by the plunger are adapted to pass through this opening 10' and to fall into a suitable recep-

tacle. The frame 12 is provided with a screw threaded opening 20 to receive the threaded portion 21 of the plunger 13, a locking collar 22 being threaded to the plunger in order that the latter may be firmly secured in place with respect to the frame.

In the operation of the device round headed bolts B are successively fed, by mechanism not shown, into the position illustrated in Figure 1 with the head of the bolt immediately in front of the square aperture 18 and the shank of the bolt aligned with the central aperture of the plunger. The frame 12 is then moved forwardly by suitable mechanism, as by the crank and connecting rod shown, this movement causing the shank of the bolt to enter the aperture in the end of the plunger thereby moving the spindle 15' and piston 15 rearwardly and compressing the spring 16. When the end of the plunger strikes the rear face of the bolt head it drives the bolt head through the opening 18' in the die plate, shearing off portions in this movement so that the head of the bolt is square when it emerges. When passing through the die the friction between the bolt head and die prevents the expansion of spring 16 but as soon as the bolt head has completed its movement through the die this frictional force no longer exists and the spring 16 immediately becomes active to move the piston 15, with its associated spindle 15', forward, and to propel the bolt out of the plunger and through the opening 10' into a receiving container. The discharge of the bolt by the mechanism illustrated is effected immediately upon the completion of the trimming operation and the plunger may be withdrawn instantly to receive a fresh blank. The action of the machine with the incorporated ejecting mechanism is therefore very rapid.

To one skilled in the art it will be apparent that numerous changes may be made in the design and arrangement of the parts of the invention which is therefore not limited to the embodiment disclosed.

Having thus described the invention what is claimed as new and desired to be secured by Letters Patent is:

1. In a bolt head trimmer, in combination, a head trimming die, a plunger movable relative to the die having an aperture in its

- end to receive the shank of a bolt and to receive a bolt ejecting spindle, said plunger being adapted to carry the bolt into head trimming engagement with the die, a spindle 5 movable into said aperture to eject a bolt shank therefrom, and means supported on the plunger and adapted to store energy therein during the forward movement of the plunger in a trimming operation through the die and to expend such energy when the 10 movement of the blank through the die is completed, to move the spindle forwardly and to eject the bolt from the aperture in the plunger.
- 15 2. In a bolt head trimmer, in combination, a head trimming die, a plunger movable relative to the die having an aperture in its end to receive the shank of a bolt and to receive a bolt ejecting spindle, a spindle 20 movable into said aperture to eject a bolt shank therefrom, and a spring supported on said plunger and adapted to be compressed during the forward movement of the plunger in a trimming operation by the entrance of the shank of the bolt into the 25 aperture in the plunger, and to expand at the completion of the trimming operation and to eject the shank of the bolt from the aperture in the plunger.
- 30 3. In a bolt head trimmer, in combination, a head trimming die, a plunger movable relative to the die having an aperture in its end to receive the shank of a bolt and to receive a bolt ejecting spindle, a chamber in rear of said aperture, said spindle being 35 movable into said aperture to eject a bolt shank therefrom, a spring in said chamber and normally holding said spindle at its forward limit of travel, the spring being 40 adapted to be compressed by the entrance of the shank of a bolt into the aperture of the plunger, during forward movement of the plunger, and to expand at the completion of the trimming operation and to eject the 45 shank of the bolt from the aperture in the plunger.
4. In a bolt head trimmer, in combination, a head trimming die, a hollow plunger movable relative to the die adapted to receive the shank end of a bolt blank and to carry the blank into head trimming engagement with the die, an ejector contained in said plunger, and means engaging said ejector 50 adapted to be energized by the working stroke of said plunger and automatically rendered active immediately after the trimming operation to cause said ejector to move axially whereby the bolt blank is ejected

from the plunger at the end of its working stroke. 60

5. In a bolt head trimmer, in combination, a die, a plunger adapted to receive the shank end of a bolt blank and press same through the die during its working stroke, and means energized by the plunger during 65 its working stroke and rendered active immediately upon completion of such stroke to eject the bolt blank from the plunger.

6. In a bolt head trimmer, in combination, a die, a plunger adapted to receive the shank 70 end of a bolt blank and press same through the die during its working stroke, and means energized by the plunger during its working stroke and rendered active to eject the bolt blank from the plunger upon completion of 75 the trimming operation independent of the movement of said plunger.

7. In a bolt head trimmer, in combination, a die, a plunger adapted to receive the shank 80 end of a bolt blank, means for effecting relative movement between the plunger and the die toward and from each other, resilient means carried by the plunger adapted to be engaged by the shank end of a bolt blank to store energy during the earlier part of the 85 relative approaching movement of the plunger and the die, means whereby the plunger engages a portion of the head of the bolt blank during the latter part of said approaching movement of the plunger and 90 die whereby the bolt blank is held in working engagement with the die until the completion of the trimming operation, whereupon said resilient means acts to expend the stored energy to eject the bolt from the 95 plunger.

8. In a bolt head trimmer, in combination, a head trimming die, a plunger having an aperture in its end to receive the shank of a bolt, and to receive a bolt ejecting spindle, 100 a spindle movable into said aperture to eject a bolt shank therefrom, means for effecting relative movement between the plunger and the die, and means supported on the plunger 105 and adapted to store energy therein during approaching relative movement between the plunger and the die in a trimming operation and to expend such energy when the movement of the blank through the die is completed, to move the spindle forwardly and 110 to eject the bolt from the aperture in the plunger.

In testimony whereof I hereunto affix my signature.

JAMES A. KINNEY.
